CLAIM

The ornamental design for a television receiver, as shown and described.

DESCRIPTION

1. Television receiver

1.1 : Front perspective view

1.2 : Rear perspective view

1.3 : Front view

1.4 : Rear view

1.5 : Left view

1.6 : Right view

1.7 : Top view

1.8 : Bottom view

1.9 : Front view, shown with the display panel in a rotated position

1.10 : Right view, shown with the hinge portion of the display panel in an alternate position

1.11 : Top view, shown with the hinge portion of the display panel in an alternate position

The subject design is a combined form between a display panel with a speaker and a stand through a dual hinge which allows the display panel and the stand to move up and down,

(Continued)

rotate and lift; the broken lines indicate portions of the article that form no part of the claimed design.

1 Claim, 11 Drawing Sheets
